(57) **CLAIM**

The ornamental design for a filtration media end cap with a unitary threaded sector, as shown and described.

DESCRIPTION

FIG. 1 is a perspective view of filtration media end cap with a unitary threaded sector, showing our new design in an environment of use;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the filtration media end cap with a unitary threaded sector of FIG. 1, shown without environmental subject matter;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

Broken lines shown in FIGS. 1-14 illustrate portions of the filtration media end cap with a unitary threaded sector that form no part of the claimed design. Additional broken lines shown in FIGS. 1-7, illustrate environmental subject matter and form no part of the claimed design.
